PACKAGE OPENING MEANS

Milton S. Meyer, Wellington, New Zealand, assignor to Wingfoot Corporation, Wilmington, Del., a corporation of Delaware

Application August 21, 1941, Serial No. 407,730

1 Claim. (Cl. 229—51)

This invention relates to a tear tape which may be used with any type of severable wrapping film, but which is designed particularly for use with a film of unoriented material. That is, a film which has no appreciable grain. A film such as Cellophane which is formed by extrusion has a grain and an ordinary tear tape may be used satisfactorily with such a film, because when one starts to tear Cellophane it will tear in a straight line. However, films of unoriented material, such as Pliofilm (rubber hydrochloride) and films of cellulose esters, such as cellulose acetate or propionate or nitrocellulose, or films of synthetic materials, such as polyvinyl compounds and other film-forming elastoplastics which are cast from a solution are unoriented. They have no grain. When one starts to open a package enclosed in such a film, if the ordinary tear tape is employed, the film will tear with a jagged edge, and the course of the tear cannot be readily directed. With the tear tape of this invention the course of the tear can be directed, and a substantially smooth edge is produced on the film. The invention will be described more particularly in connection with a tear tape of rubber hydrochloride used with a rubber hydrochloride wrapper, although it is to be understood that both the tear tape and the wrapper may be composed of other material.

The tear tape of this invention is readily torn longitudinally into three sections, and the edges of the torn tape are relatively free from irregularities. They are substantially smooth. When such a tear tape is formed on or affixed to the wrapper, the wrapper will tear with the tape. Whereas with the ordinary tear tape a wrapper of unoriented material will not tear in any predetermined direction and will give a jagged edge, with the tear tape of this invention the direction in which the wrapper is torn is controlled, and a relatively smooth edge is produced by the tear.

The invention will be further described in connection with the accompanying drawing in which Fig. 1 is a top view of a wrapped package; Figs. 2 and 3 are top views of packages with a different wrapper and tear tape arrangement; Fig. 4 is an end view of Fig. 1; Fig. 5 is an enlarged end view of the tear tape, and Fig. 6 is an enlarged section of the closure shown in Fig. 3.

The tear tape may be formed in different ways. The preferred form of tape has the same composition as the wrapping material. The packages shown in Figs. 1, 2 and 3 are covered with Pliofilm 1, and the tear tapes shown are pref-

erably composed of rubber hydrochloride. The edges 2 and 3 of the wrapper are overlapped in the usual way, and they are united in the stippled area 4 by the application of heat and pressure. Instead of a heat-seal the closure may be formed by an adhesive or in any desired manner. The tear tape 10 is advantageously located beneath the wrapper 1.

As shown most clearly in the end view illustrated in Fig. 5, the tear tape may be made of three sections or strips of material 11, 12 and 13 united to a base material 14, or, if preferred, these three sections might be united directly to the wrapper 1. The middle section has high tensile strength and the outside sections are formed of material which cannot easily be torn laterally. With this construction, with the three sections united directly to the wrapper 1, or to the base 14 which in turn is united to the wrapper 1 throughout its area, if short cuts are made in the wrapper (and also the base material 14, if one is used) in each of the spaces 15 and 16 between the sections to separate an end of the middle section from the side sections so it may easily be torn away from them, it is possible by grasping the free end of the middle section to separate it from the section on either side and also to tear away the portion of the wrapper 1 to which it is united. A path of substantially uniform width is thus cut into the wrapper. Its direction is guided by the sections or banks 11 and 13. The section 12 must have sufficient tensile strength to stand the pull required to make this tear.

If the tear tape is to be used with a Pliofilm wrapper it is advantageously made of rubber hydrochloride. The base 14 may be made of ordinary rubber hydrochloride film, or it is preferably made of film which has been heated and stretched several hundred per cent, and preferably the base 14 is built up of several plies of such stretched film, for example, three plies, each of which has been stretched several hundred per cent and all of which have been united by heat and pressure. The method of stretching and laminating several plies of rubber hydrochloride film using, in the lamination, the heat required for stretching, is old in the art. As a specific example, the base 14 may be made from three plies of Pliofilm, each 0.001 in thick which are heated and stretched to one-sixth their original thickness and united while hot by passing them between pinch rolls.

The sections 11, 12 and 13 may each be made in the same way. They may be banks of stretched rubber hydrochloride film laminated together.

Strips of rubber hydrochloride material formed in this way have great resistance to lateral tear. Thus when one starts to strip away the middle section 12 the banks 11 and 13 guide the direction in which the film tears.

If the base material 14 is formed of stretched film, whether laminated or not, it will be found that this film is oriented and normally tears in a relatively straight line, following the grain of the film. This together with the guiding banks 11 and 13 tends to cause the tear tape to tear the wrapper in a substantially straight line. It will, of course, be appreciated that the base 14 may be eliminated entirely, and the sections 11, 12 and 13 may be united directly to the wrapper. If united to the base material, and if the three sections and the base are all composed of rubber hydrochloride film, they may be united to one another in a single processing step. For example, the several plies of film required to make the tape will be heated and while hot will be stretched and then with pinch rolls they will be united to one another to form the tear tape. The several plies forming the sections 11, 12 and 13 may be united to one another and also to the base 14 in a single operation. If the base 14 comprises several plies these may be similarly united in the same operation.

It will be found desirable to fix the tear tape so that the middle section may be easily grasped and torn away from the other sections. If the film is made as shown in Fig. 5 with the sections 11, 12 and 13 all composed of stretched rubber hydrochloride film and the base 14 composed of one or more plies of stretched rubber hydrochloride film, the tear may be started by cutting the end of the tear tape so that it makes a suitable tab, such as the tab 20 of Fig. 1 or the tab 21 of Fig. 2. The base 14 being of oriented material, it will tend to tear longitudinally and if the end of the middle section can be easily grasped it will be easy to tear it away from the other sections. Following the usual practice the film and tear tape will be fed in the usual way to the wrapping machine and will be simultaneously wrapped around the package. Heat may be applied to unite the whole of the bottom area of the tear tape 10 to the wrapper 1, or an adhesive may be used for this purpose. The film and tear tape will be fed to the wrapping machine from large rolls. Sections will be cut to length in the usual way, and the wrapper and tear tape will be cut simultaneously. Thus in forming the tab 20 or 21 on the outer edge of the wrap, a complementary depression 22 or 23 is cut in the under edge of the wrap.

It will be noted that the edges of the tab 20 if projected would come within the openings 15 and 16 between the sections of the tear tape. The tab 20 may be easily grasped as shown in Fig. 4. By pulling it the base 14 of the tear tape will readily tear along the openings 15 and 16, and

the middle section of the tear tape, together with the portion of wrapper 1 which is united to it, will be torn away from the side portions of the tape, and the narrow slit thus formed in the wrapper between the side sections or guides will have relatively smooth edges.

Instead of providing a tab as shown in Fig. 1 the ends of the sections 11 and 13 may be cut away so as to leave the section 12 protruding to form the tab 21 shown in Fig. 2. Depending upon the construction of the package the heat seal may be carried straight across the package, or it may be dropped away from the end of the tear tape somewhat as shown in Figs. 2 and 3.

Fig. 4 shows another form of the invention in which the wrapper and tear tape are cut off straight, and preferably in the same operation the edge of the wrapper and tear tape are slit a short distance along the lines 24 and 25. This forms the tab 26 shown most clearly in the enlarged detail in Fig. 6. This tab is composed of the middle section of the tear tape 12 and the base to which it is united and, of course, some of the wrapper 1 to which the tear tape is united. Looking in the direction indicated by the arrows 8-8 in Fig. 3 one will see beyond the tab 26 the section 18 of the tear tape covered by the wrapper 1.

It will be obvious that many variations in the construction of the tear tape are possible. For instance, the banks or guides 11 and 13 may be formed of any suitable material which will resist lateral tearing. The different parts of the tear tape may be made of differently colored materials to add to the attractiveness of the package. The tear tape may, of course, be located in any position desired. It may be used on boxes as shown and it may be used on bags, etc. It may completely encircle the package as shown, or it may be united to only a part of the package as, for example, one face of a bag. In the preferred arrangement the edge of the tear tape will substantially coincide with an exposed edge of the film on the outside of the package, and the arrangement will be such that the middle section of the tear tape may be easily grasped and pulled away from the remaining sections.

What I claim is:

In combination with a package enclosed in a rubber hydrochloride film, a tear tape united to the film which tear tape comprises a ply of rubber hydrochloride film the width of the tape and adhered thereto three strips of permanently elongated rubber hydrochloride film, the sum of the widths of the three strips being no greater than the width of the tear tape and at one end of the tear tape at each side of the middle strip and between the middle strip and the two side strips, a slit in the wide ply of rubber hydrochloride film to facilitate the tearing thereof.

M. S. MEYER.
